United States Patent Office

Des. 204,423

Patented Apr. 12, 1966

204,423

JUG

Robert L. Bailey, Spokane, Wash., assignor, by mesne assignments, to National Distillers and Chemical Corporation, a corporation of Virginia

Filed Sept. 8, 1964, Ser. No. 81,614

Term of patent 14 years

(Cl. D58—5)

Fig. 1

Fig. 3

Fig. 2

Fig. 4

Fig. 5

FIG. 1 is a side elevation of a jug showing my new design;

FIG. 2 is an end elevational view taken from the right in FIG. 1;

FIG. 3 is a sectional view taken along line 3—3 in FIG. 2;

FIG. 4 is an end elevational view taken from the left in FIG. 1; and

FIG. 5 is a top plan view thereof.

I claim:

The ornamental design for a jug, as shown.
